WILLIAM P. GRAHAM, OF NEW YORK, N. Y., ASSIGNOR TO GRAHAM & ZENGER, INC., OF NEW YORK, N. Y., A CORPORATION OF NEW YORK

DESIGN FOR A DISH OR SIMILAR ARTICLE

Application filed January 13, 1931. Serial No. 38,295. Term of patent 14 years.

To all whom it may concern:

Be it known that I, WILLIAM P. GRAHAM, a citizen of the United States, and a resident of New York city, Borough of Manhattan, in the county of New York and State of New York, have invented a new, original, and ornamental Design for a Dish or Similar Article, of which the following is a specification.

Reference is had to the accompanying drawings, forming part thereof, wherein—

Figure 1 is a plan view of a plate showing my design, one-third being shown completed and the other two-thirds only partly completed, the completed one-third showing all the details of the design;

Figure 2 is a sectional view through Figure 1 on the line 2—2;

Figure 3 is a fragmentary detail sectional view through Figure 1 on the line 3—3;

Figure 4 is a detail fragmentary sectional view through Figure 1 on the line 4—4.

The essential features of my design comprise the curved ornamental members forming a whorl at the edge of the bottom of the plate, the same co-acting with a plurality of ornamental bars extending to the periphery.

I claim—

The ornamental design for a dish or similar article substantially as shown and described.

WILLIAM P. GRAHAM.
